UNITED STATES PATENT OFFICE.

LESLIE R. LONG, OF TIPTON, IOWA.

SHEAF-LOADER.

1,327,834.

Specification of Letters Patent. Patented Jan. 13, 1920.

Application filed December 28, 1917. Serial No. 209,253.

To all whom it may concern:

Be it known that I, LESLIE R. LONG, a citizen of the Dominion of Canada, residing at Tipton, in the county of Cedar and State of Iowa, have invented a certain new and useful Improvement in Sheaf-Loaders, of which the following is a full, clear, concise, and exact description, reference being had to the accompanying drawings, forming 10 a part of this specification.

The invention relates to harvesting machines, and primarily to that type of these devices which is designed to engage and lift sheaves or shocks of grain from the ground 15 and deposit them into a container as the machine travels across the field.

The invention has various objects, including the provision of a means for engaging, grasping, lifting and depositing a sheaf or 20 shock, and again lowering the lifting means to position it to engage another shock, upon the engagement of which a repetition of the above outlined operation takes place.

A further object of the invention is the 25 production of a means whereby the conveyer may be automatically raised and lowered, when a shock is deposited upon the conveyer and deposited therefrom. It is also an object of the invention to manually control 30 the lifting element when occasion requires this to be done.

The invention contemplates the use of a plurality of lifting elements, which are alternately raised and lowered to convey the 35 sheaves from the ground and to deposit them. These lifting elements are arranged and connected together so that upon the upward movement of one, the other is lowered. The above construction is such that one of 40 these lifting elements may be lifted and held against its downward movement without interfering in any way with the satisfactory operation of the other. This last referred to arrangement permits both of the lifting 45 elements to be brought to a raised position and locked when in this condition to facilitate the transportation of the device.

The invention further contemplates the use of a means operable from the seat for 50 unlocking the elevating elements to permit them to be released for operation.

It is a further object of the invention to

accomplish these and other advantages in a simple and expeditious manner without resulting in a corresponding reduction in the 55 efficiency in construction or operation of the machine.

The invention will be more readily understood when read in conjunction with the accompanying drawings, in which

Figure 1 is a side elevation of the device, showing the same as applied to a wagon box or body;

Fig. 2 is a sectional view taken on line 2—2 of Fig. 1;

Fig. 3 is a detail of the grasping mechanism;

Fig. 4 is a detail of the mechanism operable by the sheaf for throwing the mechanism into operative position;

Fig. 5 is a detail plan view of the winding drums used in the machine; and

Fig. 6 is a perspective view of a lock and lock releasing mechanism employed.

The invention will be explained as being 75 connected to a wagon box or body into which the sheaves are deposited, although it is evident that the apparatus may be connected directly to any other machine, such as a thresher, also that the whole apparatus may 80 be mounted upon a frame which may be interchangeably connected to either a wagon box or other machine as found desirable.

Generally speaking the mechanism for carrying out the invention will include a pair 85 of bundle receiving arms, which are alternately raised and lowered to their bundle discharging and receiving position. The means for raising and lowering these arms includes a suitable clutch mechanism which 90 is thrown into engagement with a continuously rotating shaft, which causes one of the arms to be raised, the operation of this elevating mechanism controlling the other arm as it is lowered into its bundle receiving 95 position. The deposit of a bundle upon this arm causes a repetition of the operation just described. When either of these arms reaches its uppermost position, the clutch which caused it to be raised to bundle dis-

charging position is automatically disengaged, in which position it is retained until a bundle is deposited upon the arm which is lowered.

In the embodiment of the invention as illustrated in the drawings, the use of a wagon box or body 10 having the front and rear trucks and wheels 11 and 12 is contemplated. To one of these rear wheels 12 is suitably secured the sprocket wheel 13 having the sprocket chain 14 which drives the sprocket wheel 15 arranged upon the jack shaft 16. This jack shaft is continuously rotated by the sprocket 13 and chain 14 when the wagon is drawn across the field. This jack shaft has a gear 17 which meshes with and drives the gears 18 and 19 arranged upon the shafts 20 and 21. These shafts each have a gear 22 loosely mounted thereon, which mesh with each other and drive their respective cable drums 24 and 25, when either of the clutches 26 or 27 is operated to connect said drums with the shafts 20 or 21 which are continuously rotated by the shaft 16. Each of these drums has attached thereto one end of a cable 29, which extends from the drum over the pulleys 30 and 31, and has its opposite end secured to its respective drum 24 or 25. The gears 22—22 cause the drums 24 and 25 to rotate in opposite directions which causes one of the cables 29 to be wound upon and the other let off when either of the clutches 26 or 27 is connected to drive its respective drum. Thus one of the arms 32 or 33 will be raised while the other is lowered to bundle receiving and discharging position, when either of the clutches is in operative position. These clutches are automatically disconnected by the particular arm 32 or 33 which they control when the arm has reached its bundle discharging position. The clutches 26 and 27 are both under manual and automatic control, so that either arm may be lifted over any obstacle or to its bundle discharging position. The means whereby this feature may be accomplished manually include separate instrumentalities which control each clutch. Being identical only one will be explained. This means includes the foot lever 35, shaft 36 and forked clutch lever 37. The shaft 36 is journaled in brackets 38 and 39 secured to the wagon box in the usual manner. Should it be desired to lift the arm such as 32 partially or completely, by the mechanism just described, the operator will press upon the foot lever 35. This operates the clutch 26 and connects the drum 24 with the shaft 20 causing the cable 29 of this drum to be wound thereon, which lifts the particular arm to which this cable is connected and lowers the other arm as 33, this lowering being accomplished by the gears 22. The clutch may be left in connection or disconnected which will cause the arm to be raised to its fullest extent, or only partially, as desired. The shaft 36 is provided with a lever arm 40 which is posi-

tioned thereon in the path of the arm, such as 32, to be engaged thereby to disconnect the clutch when the arm reaches its highest position. The arm 33 is provided with a lug 41 so that the arm 42 of the shaft 43 will be properly engaged to disconnect the particular clutch which the shaft 43 operates. These arms 32 and 33 are provided with means for automatically throwing the clutches 26 and 27 into operation when a sheaf is deposited thereon. This means includes the arm 44 which is positioned upon the arms 32—33 in the path of the sheaf. This arm 44 has a lever 45 to which is secured one end of a cable 46 which extends over a suitable pulley 47 and has its opposite end secured to the lever 40 or 42. Thus when the arm 44 is lowered by the sheaf, the lever 40 will be operated to throw its particular clutch 26 into operation, causing the arm to be raised and the bundle to be deposited. The clutches are thrown out of operation by the bundle carrying arm engaging its respective lever 40 or 42. Each of the bundle carrying arms 32 and 33 has pivotally secured thereto a cradle 49 into which the sheaf or shock falls when engaged thereby. This cradle has a grasping device which engages the bundle and holds same in the cradle until the arms such as 32 and 33, to which they are attached, reach their uppermost or discharging position. These cradles 49 are composed of a frame 50 having the parallel slats 51 which form the floor thereof, and the side bars 52, which retain the bundle in position thereon. The frame 50 is pivoted at 53 to the arms such as 32 and 33 and has the rearwardly extending arms 54—54, each having a roller 55. The arms 54—54 are permitted to swing to a certain limit by the chains 56. One of these arms 54 forms the actuating means for the grasping device which holds the bundle after it has been deposited upon the cradle. These grasping devices consist of the swinging bars 57—57 which are pivoted to the outermost end of the cradle, and are actuated by the lever 58 and the bell crank lever 59, which are connected together by the cord 60 which is fastened to one end of the bell crank lever. The opposite end of this bell crank lever engages and rides upon one of the arms 54 of the cradle and is actuated thereby when the arm such as 32, is raised. The grasping arm 57 is retracted by the spring 61 which releases these arms when the cradle reaches the uppermost position shown in Fig. 2. When either of the arms 32 or 33 is raised the downward swing of the cradle will cause the arms 54 to move. This causes the bell crank lever to be operated closing the grasping devices around the bundle. This condition exists until the roller 55 of the arm 54 engages the plate 63.

This causes the cradle to be turned on its pivot, releases the grasping devices, and permits the bundle to drop into the vehicle.

Each of the arms 32 and 33 is provided with a catch 64 which may be hooked over the edge of the vehicle body to hold the arm and cradle in its raised position when the machine is being transported from one place to another, and the operation of the arms is not desired. This catch is prevented from operating each time the arm reaches its uppermost position by the pivoted element 65 having the ledge 66 which is in the same plane with the portion over which the catch 15 is hooked when the arm is retained in its uppermost position. This catch rides upon the ledge and is prevented from locking the arm. The element 65 has a rod 67 which extends near the driver so that it can be 20 swung downwardly to permit the catch to operate. This element may also be operated to engage the catch to release it from its holding position when desired. The windlass has a provision which prevents the 25 operation of either of the drums when the arm which it operates is held in its upward position and which will not prevent the operation of both drums when this is desired. Thus the remaining arm may be raised without 30 operating the other drum which would unwind the cable of this drum when its particular arm is raised. To accomplish this end each gear wheel 22 is loosely arranged upon the shafts 20 and 21 and each is provided 35 with a clutch 68 which is operated to disconnect the drum and gear wheel 22, permitting one of the gears to run idle without operating its particular drum. The clutches 68 are operated by levers 68a which are controlled by any suitable means provided at 40 a convenient place near the operator.

From the foregoing explanation of the operation of the device it can readily be seen that as the device as a whole is operated 45 along the ground, and one of the clutches 26 or 27 is operated, its respective drum will be caused to revolve, winding the cable upon it and raising the particular arm to which it is attached, carrying the sheaf or shock over 50 the edge of the box or body into which the sheaf is deposited. At this time one of the levers 40 will be operated, which disengages the particular clutch which has been previously thrown into operation. It is also 55 evident that during the raising of one of the cradle arms the other will be lowered into position to engage another shock or sheaf. This operation will be continued until a sufficient number of sheaves have been collected. To insure the lowering of these arms 60 which carry the cradle, the springs 70 are provided. These springs are engaged and put under tension by their engagement with the arms 32 and 33, when these last named

elements are in their uppermost position. 65 These springs act to start the arms on their downward course when the clutches 26 and 27 of these respective arms are released. Having explained in detail one embodiment of the invention, it is obvious that changes 70 and modifications may be resorted to without departing from the spirit of the invention.

What I claim and desire to cover by Letters Patent is:

1. In a device of the class described, the combination of a pair of bundle receiving and discharging arms secured to and operable by the movement of a vehicle, each of said arms having means for raising said arms, the means of one arm being co-operatively connected with the means of the other arm, to control the lowering of one of the arms when the other is raised and means permitting one arm to be raised and lowered independently of the other. 75

2. In a device of the class described, the combination of a pair of bundle receiving and discharging arms secured to and operable by the movement of a vehicle, each of said arms having means for raising said arms, the means of one arm being co-operatively connected with the means of the other arm, and forming a means for controlling the lowering of one of the arms when the other is raised, and means preventing the operation of the raising means when one of the arms reaches its uppermost position. 90

3. In a device of the class described, the combination of a pair of bundle receiving and discharging arms secured to and operable by the movement of a vehicle, means for alternately raising said arms, the means of one arm being co-operatively connected with the means of the other arm, and forming a means for controlling the lowering of one of the arms when the other is raised, said means including means permitting one arm to be raised and lowered independently of the other. 100

4. In a device of the class described, the combination of a pair of arms constructed to be alternately raised and lowered, means for raising one of said arms, means for controlling the lowering of the other arm, and means for preventing the operation of the raising means when said arm which is raised reaches its uppermost position. 110

5. In a device of the class described, the combination of a pair of arms constructed to be alternately raised and lowered, means for raising one of said arms, means for controlling the lowering of the other arm, and means for preventing the operation of the raising means when said arm which is raised reaches its uppermost position, said means being operable by the arm when raised. 120

6. In a device of the class described, the

combination of a pair of arms constructed to be alternately raised and lowered to bundle discharging and receiving position, means for raising one of said arms, said means being operable by the bundle, and means for preventing the operation of said arm, said means being operable by the arm which is raised.

7. In a device of the class described, the combination of a pair of arms constructed to be alternately moved to bundle receiving and discharging position, means for holding one of said arms against movement, and means whereby the other arm may be moved to receive and discharge a bundle without moving the arm which is held.

8. In a device of the class described, the combination of an arm arranged to be moved in a vertical plane, a cradle having grasping means and constructed to be raised and lowered with the arm from bundle receiving to discharging position, said cradle being mounted upon the arm upon a horizontal pivot to swing from one side to the other of the arm when the arm is raised and lowered to bundle receiving and discharging position, said grasping means being automatically operable to grasp a bundle when the arm is raised and permitted to release a bundle when the arm is moved to bundle discharging position.

9. In a device of the class described the combination of an arm constructed to be moved in a vertical plane from bundle receiving to discharging position, a cradle having grasping means, said cradle and grasping means being connected together and pivoted to the arm so as to swing loosely in the same plane with the arm from one side of the pivot of the cradle to the other during the movement of the arm.

10. A device of the class described comprising in combination, an arm constructed to be raised and lowered from a bundle receiving to a discharging position, a cradle arranged upon the arm, said cradle being pivoted to the arm and movable in a vertical plane to positions upon opposite sides of the pivot, grasping means for grasping the bundle, and means for operating the grasping means, said means being arranged upon the arm, and operable by the cradle.

11. A device of the class described comprising in combination, an arm constructed to be raised and lowered from a bundle receiving to a discharging position, a cradle arranged upon the arm into which a bundle is deposited, grasping means coöperating with the cradle and means for inverting the cradle to discharge the bundle from the cradle, said means being operable to actuate the grasping means when the arm carrying the cradle is moved to discharging position.

12. A device of the class described comprising in combination, an arm constructed

to be raised and lowered from a bundle receiving to a discharging position, a cradle arranged upon the arm into which a bundle is deposited, grasping means coöperating with the cradle, and means for inverting the cradle to discharge a bundle therefrom, said means being operable to actuate the grasping means to grasp and release a bundle.

13. A device of the class described comprising in combination, an arm constructed to be raised and lowered from bundle receiving to discharging position, the arm being arranged to assume a substantially vertical position when raised, a cradle pivoted to the arm, means for grasping a bundle, means whereby the cradle is operated to discharge the bundle therefrom, said means including a means whereby the cradle is turned upon its pivot and inverted to discharge the bundle therefrom, and serving to release the grasping means when the cradle is inverted.

14. A device of the class described comprising in combination, an arm constructed to be raised and lowered from bundle receiving to discharging position, the arm being arranged to assume a substantially vertical position when raised, a cradle pivoted to the arm and means whereby the cradle is turned upon its pivot and inverted to discharge the bundle therefrom.

15. A device of the class described comprising in combination, an arm constructed to be raised and lowered from bundle receiving to discharging position, means for raising said arm, means for preventing the operation of said arm, said last mentioned means being operable by the arm, a cradle arranged upon the arm, grasping means, said grasping means being operable by the cradle, and means for discharging the cradle, said means being operable by a means arranged upon the cradle.

16. A device of the class described comprising in combination, an arm constructed to be raised and lowered from bundle receiving to discharging position, means for raising said arm, means for preventing the raising of said arm, said last mentioned means being operable by the arm, a cradle arranged upon the arm, grasping means operable by the cradle, and means for discharging the cradle, said means being operable by a means arranged upon the cradle, and said means forming a means for releasing the grasping means.

17. A device of the class described comprising in combination, an arm constructed to be raised and lowered from bundle receiving to discharging position, a cradle arranged upon the arm, said cradle having grasping means, means for actuating the grasping means, the cradle being pivoted to the arm and having a member extending therefrom, said member providing means for actuating the grasping means and to ro-

tate the cradle to discharge the same when the arm is raised, and means for engaging said member to cause the rotation of the cradle.

5 18. A device of the class described comprising in combination, an arm constructed to be raised and lowered from bundle receiving to discharging position, a cradle pivoted upon the arm, and having a portion extending in a direction opposite to the cradle, grasping means arranged upon the cradle and means arranged upon the arm for operating the grasping means, said last mentioned means being operated by the portion 10 which extends from the cradle.

15 19. In a device of the class described, the combination of an arm arranged to swing from bundle receiving to bundle discharging position, a cradle having grasping means 20 provided upon the arm, said cradle and grasping means being arranged to assume a position upon one side of the arm when lowered to receive a bundle and to assume a position transverse to the arm when the arm 25 is raised to discharge the bundle, and the cradle and arm being movable in planes which correspond to each other when moved to receiving and discharging position, and means for operating the grasping means to 30 release the bundle when the cradle assumes a position upon one side of the arm.

20 20. In a sheaf loading device, the combination of a pair of bundle receiving and discharging arms, a pair of winding drums one 35 for each arm, means for driving the drums, means connecting each arm with its respective drum, means connecting both drums together to control the lowering of one arm when the other is raised, and a clutch for 40 each drum operable to actuate the drum to raise the arm connected to the drum.

25 21. In a device of the class described, the combination of a bundle receiving arm constructed to be raised and lowered to receive 45 and discharge a bundle, means provided upon the arm for holding said arm in raised position, and means constructed to be positioned to prevent the operation of the holding means when said arm is raised and lowered 50 and to permit the first mentioned means to hold the arm in raised position upon the operation of the second mentioned means.

22. In a device of the class described, the combination of a bundle receiving arm ar-

ranged to be raised and lowered to receive 55 and discharge a bundle, said arm being secured to a vehicle and constructed to carry the bundle from one side of the vehicle to the other, said arm having means constructed to engage the vehicle to hold same in elevated position, and means normally arranged to prevent the operation of the holding means to permit the arm to be raised and lowered.

23. In a device of the class described, the combination of a pair of bundle receiving and discharging arms secured to and operable by the movement of the vehicle, means for raising either of said arms and lowering the other when the former is raised, the 60 means of one arm being operably connected with the means of the other arm and controlling the lowering of one of the arms when the other is raised.

24. In a device of the class described, the combination of a pair of bundle receiving and discharging arms, each arm having means whereby it may be raised, means for operating either of said means and means connecting both of the first mentioned means 80 said means controlling the lowering of one arm when the other is raised.

25. In a device of the class described, the combination of a pair of bundle receiving and discharging arms, each arm having 85 means whereby it may be raised, a shaft for operating said means of each arm, a connection between said means whereby one arm is raised and the other lowered and clutches arranged between said means and 90 the shaft for causing the operation of the raising means.

26. In a device of the class described, the combination of a continuously rotating shaft, a pair of bundle receiving and discharging arms, means for causing said arms to be raised and lowered, means for connecting said last mentioned means with said shaft to cause the operation of the raising means said raising means of one arm being 100 operably connected with the raising means of the other arm to cause one of said arms to be lowered when the other is raised.

In witness whereof, I hereunto subscribe my name this 10th day of December, A. D., 105 1917.

LESLIE R. LONG.
